UNITED STATES PATENT OFFICE.

CHARLES ALLEN, OF EL PASO, TEXAS.

CLOSED GRINDING CIRCUIT.

1,408,155.

Specification of Letters Patent. Patented Feb. 28, 1922.

Application filed June 10, 1920. Serial No. 387,887.

To all whom it may concern:

Be it known that I, CHARLES ALLEN, a citizen of the United States, residing at El Paso, in the county of El Paso and State 5 of Texas, have invented a new and useful Improvement in Closed Grinding Circuits, of which the following is a specification.

This invention relates to closed grinding circuits wherein a classifier, dewaterer or 10 the like is used in combination with a pulverizer.

The object is to improve the efficiency of such a grinding circuit. In carrying out this object, I arrange in combination an 15 automatically controlled spigot discharge classifier or dewaterer in position to deliver its classified product to a pulverizer, and an air-lift to receive the material from the pulverizer and return it to the classifier or de- 20 waterer.

Solids fed to ball mills or tube mills should be accompanied by only a small quantity of water, approximately 30% water to 70% solids by weight. All feed streams 25 that will freely flow down launders must be dewatered or partially dewatered before entering the mill, and effective hydraulic classification is impossible when the feed stream is composed of 30% water and 70% 30 solids. Therefore, water must be added to the ball mill discharge for classification purposes and the particles to be reground must be delivered to the ball mill in a dewatered condition. The efficiency of the pulverizer 35 very largely depends upon the perfectness and uniformity of the classification and the dewatering. By the present invention, I am enabled to meet these conditions ex- 40 actly regardless of fluctuations in the char- acter or in the volume in the primary feed.

In the accompanying drawings,

Fig. 1 shows a vertical central sectional view of the combination constituting the present invention and employing a pre- 45 fered type of classifier.

Fig. 2 shows a similar view of the combination employing a classifier or sand trap.

In the drawings, I show a ball mill 10 with a primary feed spout or launder 11. 50 The mill discharges at 12 into a well 13 which is supplied with water from a valved pipe 14. Extending from the bottom of the well to a point above the ball mill is an air-lift tube 15 arranged at the upper end 55 of which is a receptacle 16, including a deflector 17 overlying the upper end of the air-

lift tube and spaced therefrom. Within the tube 15 is a compressed air-pipe 18 extending from an outside source of supply downwardly within the tube 15 to a point near 60 the bottom of the latter where the said tube 15 is flared outwardly and is provided with perforations or apertures 15^a to admit material from the well to the interior of the tube. 65

Air under pressure discharge from the pipe 18 will lift the material in the tube 15 and discharge it into the receptacle 16, the deflector 17 preventing the material from being blown out of the receptacle. 70 From the receptacle 16 the material passes into a launder 18' which communicates with a classifier or dewaterer.

As shown in Fig. 1, the classifier or de- 75 waterer is in the form of a cone 20 having a bottom discharge orifice controlled by a valve 21. This valve 21 is automatically actuated by connections 22 with a float 23, which float is arranged near the top of the tank surrounding a feed spout or pipe 24 80 into which spout or pipe the material from the launder 18' passes.

Material enters the tank 20 from the launder 18 and the lighter and more slowly settling particles will overflow the rim of 85 said tank and pass out through a discharge spout 25 into a discharge launder 26. The heavier and more quickly settling particles will accumulate in the bottom of the tank, it being understood that the valve 21 is nor- 90 mally held in closed position by the weight of the float 23. When the accumulated material in the tank reaches a predetermined density, the float 23 will be raised, thereby opening the valve 21 and allowing the set- 95 tled material to escape. The classifier is arranged above the feed launder 11 and the material discharged through the spigot of said classifier enters the ball mill through said feed launder where it is reground and 100 discharged again into the well 13.

In Fig. 2, I show an automatic sand trap in place of the classifier just described. It includes a cone-shaped tank 28 supported by lugs 29 on springs 30, which springs are se- 105 cured to upright posts 31. The tank has a bottom discharge orifice 32 normally closed by a valve 33 whose stem extends upwardly through the tank and is secured to a spider 35 fastened to the posts 31. Normally, the 110 springs 30 keep the tank so elevated as to maintain the discharge orifice closed. The

material enters the tank through the launder 18' as in the case of Fig. 1 and the lighter product overflows the rim of the tank or passes out through a spout 36 into a discharge launder 37, while the heavier product accumulates in the bottom of the tank until the weight thereof causes the tank to be lowered depressing the springs and opening the discharge orifice 32, whereupon the product to be further comminuted will pass out into the primary feed launder 11, as in the case of Fig. 1.

The uniform percentage of water to solids in the spigot discharge of the automatic classifier is due to the continuous maintenance of settled solids in that portion of the tank overlying the discharge orifice. The discharge closely approximates 30% water to 70% solids when the solids are 2.64 specific gravity and as these percentages are automatically continuously maintained, the automatic classifier is peculiarly adapted to closed circuit grinding. Without automatic control of the area of the spigot outlet such results are unobtainable.

A given area of spigot orifice is the correct area for a certain volume and character of discharge only. If the quantity of solids that should be discharged through the spigot orifice increases in the feed stream, the result is the filling up of the classifier, and the overflowing of particles that should have been discharged through the spigot for further comminution, and when the quantity of solids that should be discharged through the spigot orifice diminishes in the feed stream, then particles that should overflow the classifier are discharged through the spigot and if this condition prevails for a short time, the classifier is emptied of settled particles. Hence, the advantage of the automatic control of the spigot orifice.

Various changes in the construction and

arrangement of the several parts may be employed without departing from the spirit 45 of my invention as disclosed in the appended claims.

Having thus described my invention, what I claim and desire to secure by Letters Patent is:

1. A closed grinding circuit, including a pulverizer, an elevator into which the pulverized material discharges, a classifying and dewatering vessel to receive the material from the elevator, said vessel having a rim overflow for light and slowly settling particles and a bottom discharge orifice for quickly settling and heavy particles, means actuated by changes in the density of the material in the vessel for controlling said bottom discharge orifice, and means to return the classified and dewatered material to the pulverizer. 55

2. A closed grinding circuit including a pulverizer, an elevator into which the pulverized material discharges, a classifying and dewatering vessel to receive the material from the elevator, said vessel having a rim overflow for light and slowly settling particles and a bottom discharge orifice for quickly settling and heavy particles, a valve 70 to control the bottom discharge orifice, a float within the vessel responsive to changes in the density of the material within to rise and open the valve when such material reaches a predetermined density, and means to return the classified and dewatered material to the pulverizer. 75

In testimony whereof I have hereunto set my hand in the presence of two subscribing witnesses.

CHARLES ALLEN.
